(57) **CLAIM**

The ornamental design for a T-shaped handle, as shown and described.

DESCRIPTION

FIG. 1 is a perspective view of a T-shaped handle. The handle is shown attached to a shaft in a conventional tray. FIG. 2 is a front view of the T-shaped handle of FIG. 1. FIG. 3 is a back view of the T-shaped handle of FIG. 1. FIG. 4 is a top view of the T-shaped handle of FIG. 1. FIG. 5 is a bottom view of the T-shaped handle of FIG. 1. FIG. 6 is a right-side view of the T-shaped handle of FIG. 1; and, FIG. 7 is a left-side view of the T-shaped handle of FIG. 1. The broken lines are for illustrative purposes only and form no part of the claimed design.
